WATCHBAND DISPLAY BOX

Michael P. Arnone, North Bergen, N.J., assignor, by mesne assignments, to Kreisler Manufacturing Corporation, North Bergen, N.J., a corporation of Delaware

Filed Mar. 3, 1969, Ser. No. 15,985

Term of patent 14 years

Int. Cl. D9—04

U.S. Cl. D9—237

FIG. 1 is a perspective view of a watchband display box, showing my new design;

FIG. 2 is a top plan view;

FIG. 3 is a side elevational view; and

FIG. 4 is a bottom plan view thereof.

I claim:

The ornamental design for a watchband display box, substantially as shown.
